UNITED STATES PATENT OFFICE.

WILLIAM OSCAR DRESSER, OF CRIPPLECREEK, COLORADO.

MAIL-BOX.

No. 805,351.

Specification of Letters Patent.

Patented Nov. 21, 1905.

Application filed February 4, 1905. Serial No. 244,145.

To all whom it may concern:

Be it known that I, WILLIAM OSCAR DRESSER, a citizen of the United States, residing at Cripplecreek, in the county of Teller and State 5 of Colorado, have made certain new and useful Improvements in Mail-Boxes, of which the following is a specification.

My invention is an improvement in mail-boxes intended for use for street and rural 10 delivery of mail-matter; and the invention consists in certain novel constructions and combinations of parts, as will be hereinafter described and claimed.

In the drawings, Figure 1 is a front view; 15 Fig. 2, a side view; Fig. 2^a, a detail cross-section on about the line 2^a 2^a of Fig. 2, and Fig. 3 a cross-section on about the line 3 3 of Fig. 1, of a box embodying my invention. Fig. 4 is a longitudinal section on about the 20 line 4 4 of Fig. 1. Fig. 5 is a longitudinal section on about the line 5 5 of Fig. 4. Fig. 6 is a detail section on about the line 6 6 of Fig. 2. Fig. 7 is an elevation of a portion of the inner side of the door, showing the 25 combination-lock thereon; and Fig. 8 shows a box adapted to be cast in aluminium or suitable metal.

By my invention I provide a novel construction of box made of metal and suitably 30 constructed of the different plates secured together, as will be described.

As shown, the box includes the base-plate A, the top plate B, the body-plate having the front section C and the side sections D, said 35 front and sides C and D being integral, as best shown in the detail Fig. 2^a, and the bottom plate E. The plates B, D, and E are provided at their inner edges, respectively, with lateral flanges B', D', and E', which are lapped 40 against and riveted or otherwise secured to the base-plate A, as shown at a in Fig. 1. The plates D are provided at their upper ends at their front corners with the upwardly-projecting lugs d, to which is pivoted at f the lid 45 F, which covers the letter-slot C² in the front plate or section C. As shown in Fig. 4, the top plate B extends forwardly between the lugs d and beneath the pivot f and has a downwardly-bent flange b, which forms the 50 top wall of the slot C², the lid F curving at F' forwardly over the front edge of the top plate B, as the pivot f is located slightly in rear of the front edge of the top plate, as will be understood from Fig. 4 of the drawings. 55 By this means I shed water from the opening C² and prevent water from entering the box

through the said opening. At its opposite sides the top plate B is provided with depending flanges B², which overlap the upper ends of the side plates or sections D, said 60 flanges B² terminating at b² close to the rear edges of the lugs d, as shown in Fig. 2 of the drawings.

At their lower ends the side plates or sections D are provided with the inwardly-projecting flanges D², which lap beneath the bottom plate E, said flanges D² and the flanges B² of the top plate being riveted or otherwise secured to the plates which they overlap, thus forming a box which is strong and rigid in 70 use.

The front plate or section C is provided with a door-opening C', which is closed by the door G, hinged at G' at one edge and provided at its other edge with a bolt G², which 75 may be engaged with a suitable stop G³ in the letter-box, as shown in Fig. 3, to lock the door. The bolt G² is part of a combination-lock H, having the dials I controlling the movements of the bolt, which latter is arranged for operation by the handle J. Manifestly the form of the combination-lock may be varied, and it is not necessary to show the same in detail herein; but I have illustrated in Fig. 7 an elevation of the inner side of the 85 lock and it is not thought necessary to describe it in detail. A combination-lock for this purpose would be found efficient and very convenient. I also provide the door G with an opening covered by a glass plate g, 90 so the contents of the box may be seen at any time.

Letters and the like may be inserted through the slot C², and I find it convenient to provide means for holding newspapers and similar packages. For this purpose I employ a spring-wire bail K, which at its middle bears against the front of the box, as shown in Figs. 1 and 2, and extends for its major portion approximately parallel with the front of 100 the box, as shown in Fig. 2, and then has its arms deflected rearwardly at K' alongside the box and then extended downwardly at K² and provided with a series of coils K³ with the extended ends K⁴ secured to the sides of the box 105 at K⁵, it may be, by bending said ends into sockets in the sides of the box, as will be understood from Figs. 1 and 2. I find it convenient to brace the bail and to confine the coils K³ by means of hooks L, (see Figs. 1, 2, 110 and 6,) the hooks extending through the coils and operating to retain the same and also to

stay the wire bail, as will be understood from Figs. 2 and 6 of the drawings.

Where desired, a name-plate M of suitable metal may be provided in the front of the box 5 to receive the name of the owner of the box or the number of the house or for any other purpose desired.

In Fig. 2 the drop-lid F is shown closed in full lines and open in dotted lines, and when 10 arranged as shown it can be thrown open and will remain so while letters are being placed into the box.

In practice I find it desirable to construct the box of metal and find when made as shown 15 and described it will form a safe and convenient place for reception of mail-matter.

It may be desirable in some instances to cast the letter-box in aluminium for attachment to office-doors, club-rooms, rooming-houses, &c., 20 and I show such a construction in Fig. 8, in which the box is provided at its upper end with a lug O to receive a screw for securing the upper end of the box, a lower screw O' being passed through the back of the box, so that 25 the latter will be securely held to the door or other support.

Having thus described my invention, what I claim as new, and desire to secure by Letters Patent, is—

30 1. The improvement in mail-boxes herein described comprising the base-plate, the main plate having the front and side sections and having the latter provided at their inner edges with lateral flanges lapping against and secured to the base-plate and the front plate or section being provided at its upper end with a letter-slot and at its lower end with a door-opening, the door fitted to said opening and hinged at one edge and provided at its other

edge with a combination-lock having a bolt by 40 which to hold the door closed, the side sections of the main plate being provided at their lower ends with inwardly-projecting flanges overlapping the bottom plate and also provided at their upper ends at their front corners with the upwardly-projecting lugs, the bottom plate secured to the inwardly-projecting flanges of the side sections and provided at its inner edge with the flange lapping against and secured to the base-plate, the top plate 45 having at its inner edge the flange lapping against and secured to the base-plate, provided at its side edges with depending flanges overlapping the side sections of the main plate and having at its front edge a depending flange 50 forming the top wall of the letter-opening, the drop-lid pivoted to the upwardly-projecting lugs of the side sections, and curving thence and adapted to close the letter-slot, the spring-bail for holding newspapers having its arms 55 coiled and extending beyond said coils and secured to the sides of the letter-box, and the hooks projecting from the box through and engaging with said coils, substantially as and for the purpose set forth.

65 2. The combination in a letter-box with the front plate or section having a letter-slot and the side plates or sections having the upwardly-projecting lugs at their front edges, of the top plate projecting at its front edge between 70 said lugs, and the drop-lid pivoted to said lugs above the front edge of the top plate and adapted when lowered to close the letter-slot, substantially as set forth.

WILLIAM OSCAR DRESSER.
